UNITED STATES PATENT OFFICE.

CHARLES M. DAY, OF HOPEDALE, MASSACHUSETTS, ASSIGNOR TO DRAPER COMPANY, OF PORTLAND, MAINE, AND HOPEDALE, MASSACHUSETTS.

MOLDING APPARATUS.

SPECIFICATION forming part of Letters Patent No. 726,515, dated April 28, 1903.

Application filed October 7, 1901. Serial No. 77,834. (No model.)

To all whom it may concern:

Be it known that I, CHARLES M. DAY, a citizen of the United States, residing at Hopedale, in the county of Worcester and State of Massachusetts, have invented an Improvement in Molding Apparatus, of which the following description, in connection with the accompanying drawings, is a specification, like letters on the drawings representing like parts.

This invention relates to that type of machine-molding apparatus wherein the pattern is supported by or secured to a so-called "vibrator-frame," shaped exteriorly to correspond with the match-frame upon which it rests and with the drag and cope flasks, the vibrator-frame being interposed between said flasks and vibrated preparatory to the removal of the cope and afterward when the pattern is drawn from the drag, one form of such type of apparatus being shown in United States Patent No. 654,292, dated July 24, 1900. As the frame rests directly upon the drag-flask and in turn supports the weight of the cope, the friction is considerable on the contacting surfaces of the several parts, so that the response of the frame to tapping is very sluggish, and to set up sufficient vibratory motion therein to properly separate the pattern from the sand quite heavy blows must be struck by the vibrating device, one well-known form of which is operated by compressed air. In practice the slighter the vibration of the pattern-supporting or vibrator frame to enable it to be withdrawn from the sand the better and more accurate the mold, and in my present invention I have provided means for sustaining the vibrator-frame in such manner that it is readily and quickly responsive to very slight blows, and preferably the frame is sustained at its corners.

In the present embodiment of my invention the vibrator-frame is adapted to be sustained in a yielding manner between the drag and cope flasks before their separation, so that the least jar or blow thereupon will set up sufficient vibration in the frame, and the means sustaining said frame will act promptly to restore it to its normal position or into the exact position it occupied when the sand was rammed upon it.

Figure 1, in plan view, shows a vibrator-

frame illustrating my invention in one of the best forms now known to me; and Fig. 2 is a side elevation of the same, partly broken out, to show more clearly one of the yielding supports, the drag and cope flasks being indicated by dotted lines.

The vibrator-frame A, having ears a by which to handle the same, and supporting within it the pattern a' and gate a'', are and 55 may be all as usual in molding apparatus of the type referred to, a vibrator V being shown attached to the frame.

In accordance with my invention I provide the frame, which is or may be of any usual or 65 suitable shape, with widely-separated supports b, preferably composed of india-rubber or other elastic or resilient and yielding material, the ends of the supports, herein shown as cylindrical plugs, projecting slightly beyond 70 each face of the frame and secured in holes in the latter, the supports being shown as arranged symmetrically.

When the ends of the supports contact with the opposed edges of the drag and cope flasks 75 D and C, respectively, as shown in Fig. 2, the vibrator-frame when the mold is finished may be readily vibrated or moved by a very slight blow or series of blows, the supports yielding readily to such vibrational movement, and the natural resiliency of the supports will act immediately upon stoppage of the vibrator to return the frame and pattern into substantially the exact position occupied when the drag or the cope were rammed. 85

Instead of making the supports of india-rubber they might be made of metal in the form of spiral or other springs.

Having fully described my invention, what I claim as new, and desire to secure by Letters 90 Patent, is—

A vibrator-frame for molding apparatus, having symmetrically-arranged elastic supports mounted thereon and projecting beyond the opposite faces thereof.

In testimony whereof I have signed my name to this specification in the presence of two subscribing witnesses.

CHARLES M. DAY.
